UNITED STATES PATENT OFFICE.

RICHARD SCHULZE, OF WALLINGFORD, CONNECTICUT, ASSIGNOR TO INTERNATIONAL SILVER CO., OF MERIDEN, CONNECTICUT, A CORPORATION OF NEW JERSEY.

DESIGN FOR A SPOON, FORK, OR SIMILAR ARTICLE.

42,977.

Specification for Design.

Patented Sept. 3, 1912.

Application filed June 10, 1912. Serial No. 702,890. Term of patent 7 years.

To all whom it may concern:

Be it known that I, RICHARD SCHULZE, a citizen of the United States, residing at Wallingford, in the county of New Haven and State of Connecticut, have invented a new, original, and ornamental Design for a Spoon, Fork, or Similar Article; and I do hereby declare the accompanying drawing to be a full, clear, and exact illustration of the same, and which said drawing constitutes part of this application, and represent, in—

Figure 1 a face view of a spoon, fork or similar article embodying my design. Fig. 2 is a detail perspective view.

I claim:

The ornamental design for a spoon, fork or similar article, as shown.

RICHARD SCHULZE.

Witnesses:

JOHN A. MARTIN,
E. E. BALL.
